MANICURE DEVICE

William E. Shore, West New Brighton, N. Y.

Application October 7, 1940, Serial No. 360,017

11 Claims. (Cl. 132—75.6)

This invention relates to a manicure device and has for an object the provision of improvements in this art. The device which is provided by the invention is adapted to be carried on the person of the user for ready accessibility at all times. It is so designed that it is of small size and may be carried in the pocket or handbag. It comprises elements which serve all normal requirements of keeping the hands in neat and clean condition, such elements being a file, a pointed scraper or tooth, a brush, a nail smoothing element, a supporting clip, and possibly elements for other purposes. The parts or elements are mutually interrelated in a novel manner to protect the elements, aid in the use of the device, and to protect the person, pocket or handbag of the user from injury.

Many persons, of whom doctors and nurses may be mentioned, must constantly clean their hands as an essential of their business, and others do so for appearance and cleanliness. Each time the hands are washed the nails may be scrubbed with a brush, using soap and water. But though the hands may be washed many times a day a nail brush may not always be available. Because it is too large and remains wet after use it is not desirable to carry the old type brush on the person. Nor is it always desirable to use a wet brush even when available, because it may be accessible to the general public. The brush provided by the present invention is adapted to be used dry or substantially so and its inbuilt characteristics are best realized when used dry. Preferably it is used just after washing the hands while the nails are still moist but this moisture is not sufficient to soften the bristles as is the case when a brush is constantly used in water nor does it discourage carrying the device about on the person of the user. However, the device comprises a pilot rail and guard plate which, though primarily intended for guiding the nails when using the brush, serves to partially enclose the brush and this makes it practically unobjectionable to carry the brush even if wet.

This guard plate fully protects the bristles of the brush from damage and also protects the person and effects from damage by the nail scraper or tooth.

The above and other objects and features of the invention will be apparent from the following description of certain illustrative embodiments thereof, reference being made to the accompanying drawing thereof wherein:

Fig. 1 is a front view of one embodiment;
Fig. 2 is a rear view;
Fig. 3 is an end view;

Fig. 4 is an enlarged partial rear view;
Fig. 5 is an enlarged end view partly in section;
Fig. 6 is a rear view of a modification;
Fig. 7 is a bottom edge view of Fig. 6;
Fig. 8 is a rear view of a modified guard plate; and

Fig. 9 is a section on the line 9—9 of Fig. 8.

Referring to the drawing the device comprises a brush holder 10 which may be of wood, plastic composition, suitable metals or other desired material into the upper edge of which a row of bristles constituting a brush 11 is set. There is secured to the back of the holder a guard plate 12 and pilot rail 12a, here shown as an integral unit with the plate. This plate and rail unit may be formed of any suitable material, wood, metal or composition and preferably is transparent in order to view the bristles and insure that they are kept clean. It may be secured to the holder by screws, rivets or the like 13; or with certain materials and by certain methods of manufacture may be made integral with the holder. Between the plate and the holder there may be secured a sheet on which advertisements or directions for use may be placed.

A file 14 may be secured to the lower edge of the holder, for example, being held in a groove thereof, by clamping it under the guard plate 12, by cementing, or otherwise. The file, if it extends beyond the surface of the holder, may be roughened on both sides and be of the same or different coarseness. The lower edge of the holder or guard plate, or both, thus present edges 15 parallel to the edge of the file for guiding the nails therealong, as indicated in Fig. 5.

The guard plate 12 may extend beyond the ends of the holder and is there shaped to provide scrapers or teeth 16 for cleaning beneath the nails. The guard plate is provided with slots 17 above the teeth 16 to receive the ends of the nails and curved recesses 18 below the teeth to receive the ends of the fingers.

A groove 19 may be formed on the holder for rubbing the ends of the nails to smooth them, as shown in Fig. 5.

The bristles are set in such a way as to place them upon tension and keep their upper ends spaced from the guard plate 12 and nail pilot rail 12a which is formed with an angular bend away from the bristles. The bristles are set in the holder at an angle to its plane, as shown in Fig. 5, but are bent back by a tension rail 22 secured to the guard plate near the base of the bristles. If desired the tension rail may be secured by being formed integral with the guard plate. This pres-

sure of the tension rail causes the bristles to fan out along the length of the guard plate, to be sharpened at their ends for entry under the nails, and to stand firm slightly clear of the guard plate and pilot rail to allow the nails to move easily therebetween. As shown in Fig. 5, the angle of the bristles to the holder plane and guard plate plane may preferably be about 20°. Likewise the angle of the pilot rail to the guard plate may be the same, or 20°.

The ends of the teeth 16 are set back from the ends of the guard plate on a line making an angle of about 30° with the ends extended (Fig. 4).

The teeth, instead of being formed on the guard plate itself, may be formed on the ends of the file 14' as at 16' in Figs. 6 and 7. This is a harder material and better adapted to do heavy scraping than the material of the guard plate. The disposition of the teeth is the same as before except that their ends are bent up into the plane of the guard plate 12' for protection as shown in Fig. 7. The teeth may be formed at an angle on their upper edges to make a sharp front line for better scraping action though this may be rounded slightly to avoid too harsh action. Also, as shown in Fig. 7, the ends of the teeth may be formed on a slight angle, say 6° from perpendicular to the plane of the brush. The tooth at each end may thus be adapted for the nails of each hand respectively.

One or all forms may be provided with a clip 25 for securing it to the pocket. This may be attached, as shown in Figs. 6 and 7, or be formed of the material of the guard plate, as shown at 25' in Figs. 8 and 9. In Figs. 6 and 7 corresponding parts are designated by the same reference characters as in Figs. 1-3 but with a prime (') added and similarly in Figs. 8 and 9 a double prime (") is added.

It will thus be seen that the invention provides a small compact unitary device of several elements in combination which are mutually interrelated with each other and together serve all purposes required in manicuring the nails. The file is protected in the holder and the lower edge of the holder or guard plate or both serve as convenient guides for the nails in using the file. The holder anchors the bristles while the tension plate cooperates to shape and stiffen them. The pilot rail directs the nails accurately in using the bristles forming the brush. The guard plate and its extended ends serve to protect the bristles and the ends protect the cleaning teeth. Incidentally the upper edge of the pilot rail may be of considerable service as a straight edge for drawing lines of sketches and may be marked with a scale if desired.

While certain embodiments of the invention have been illustrated and described it is understood that the invention may have various other embodiments within the limits of the prior art and the scope of the subjoined claims.

I claim:

1. A manicure device comprising in combination, a holder, a row of bristles set at a plane angle in the edge of the holder, a plate secured along one side of the bristles, and means on the plate to press the bristles back to cause their ends to stand away from said plate and form a thin edge and to place them under tension.

2. A manicure device comprising in combination, a holder, a nail file secured on the lower portion thereof so that an edge of the holder serves as a guide for the file, a row of bristles forming a brush at the upper portion of the

holder, a guard plate secured alongside the bristles and including an angular nail guide rail to guide the nails down behind the bristles and to protect the bristles, said bristles being disposed to provide a thin edge spaced from the angular nail guide rail at their upper ends and said guide rail being disposed along a plane which strikes the bristles below their upper ends, the ends of said guard plate extending beyond the ends of the holder, and cleaning teeth at the ends of the holder protected by the ends of the guard plate.

3. A manicure device as set forth in claim 2 which is further provided with a smooth nail burnishing groove on the side opposite said guard plate.

4. A manicure device comprising in combination, a holder, a row of bristles in one edge thereof, a guard plate along one side of the bristles which includes an angular nail guide rail for entering and directing the nails, said bristles being disposed to provide a thin edge spaced from the angular nail guide rail at their upper ends and said guide rail being disposed along a plane which strikes the bristles below their upper ends, and cleaning teeth at the ends of the holder, the projecting ends of the plate protecting the cleaning teeth.

5. A manicure device comprising in combination, a holder, a row of bristles set at a plane angle in the edge of the holder and having a thin upper edge, a guard plate secured along one side of and spaced from the bristles and having its top edge diverging angularly away from the bristles below their tops to form a pilot rail to direct the nails downward and behind the top of the bristles.

6. A manicure device comprising in combination, a holder, a row of bristles set in the edge of the holder, a guard plate secured to the holder behind the bristles, said guard plate extending beyond the ends of said holder, and cleaning teeth at the ends of the holder aligned with and spaced a short distance below said guard plate ends, the ends of the teeth being shorter than the ends of the guard plate whereby the hands and apparel are protected from injury by the teeth.

7. A manicure device as set forth in claim 6 further characterized by the fact that said teeth are concave on their lower edges to fit the ends of the fingers when the teeth are disposed under the finger nails.

8. A manicure device as set forth in claim 6 wherein said teeth are concave on their lower edges and beveled across their upper edges for the purposes set forth.

9. A manicure device comprising in combination, a holder, a nail file secured in the lower portion thereof so that an edge of the holder serves as a guide for the file, the ends of the file being formed to provide cleaning teeth, and a guard plate secured on the holder and being provided with projecting ends extending beyond the ends of the cleaning teeth and spaced slightly from them to protect them.

10. A manicure device as set forth in claim 9 in which said guard plate secures the nail file to the holder.

11. A manicure device as set forth in claim 9 in which the longitudinal edges of the holder and guard plate form approximately right angles with the file faces for guiding the nails along the file.
